Primary Examiner — Patricia Palasik(74) *Attorney, Agent, or Firm* — Wood, Herron & Evans, L.L.P.(57) **CLAIM**

The ornamental design for the upper portion of a wall mounted adhesive melter, as shown and described.

DESCRIPTION

FIG. 1 is a perspective view of the upper portion of a wall mounted adhesive melter according to the present invention. FIG. 2 is a front elevational view of the upper portion of a wall mounted adhesive melter according to the present invention. FIG. 3 is a left side elevational view of the upper portion of a wall mounted adhesive melter according to the present invention.

FIG. 4 is a right side elevational view of the upper portion of a wall mounted adhesive melter according to the present invention; and,

FIG. 5 is a top elevational view of the upper portion of a wall mounted adhesive melter according to the present invention. The broken lines define unclaimed boundaries of the design.
